MULTIPLE DOOR COMPARTMENT

Ellis J. G. Phillips, Aurora, Ill., assignor to
 Richards - Wilcox Manufacturing Company,
 Aurora, Ill., a corporation of Illinois

Application December 1, 1930, Serial No. 499,268

6 Claims. (Cl. 312—191)

This invention relates to compartments having connected doors wherein access to the interior of the compartment is gained only by the operation of one of the doors, commonly known as a master door. This compartment is particularly adapted to be used for wardrobes or locker rooms in schools, churches, gymnasiums, bath houses, or in any location wherein it is advantageous to control a number of doors in a structure by a master door, thus obviating individual locking mechanisms, keys, and other hardware for each of the doors, and incidentally affording centralized control and responsibility of the property to be left in such a compartment.

An object of this invention is to provide an improved arrangement of operating mechanism for multiple doors or closures, wherein each door or closure is dependent upon a master door for opening and closing.

Another object of the invention is to mount the doors in an improved manner to have an improved operating movement whereby a series of doors may be opened to a maximum extent to give free and easy access to all parts of the interior of the compartment.

Another object of the invention is to provide a construction wherein all of the doors of the series move substantially entirely into the compartment so as to be out of the way when in open position.

This is a very advantageous feature when the compartment is to be used in schools or the like having a minimum of space in front of the compartment, and particularly where it is desirable to avoid having the doors obstruct an aisle or passageway between the compartment and a row of desks or the like, when the doors are in open position. The opening and closing of my improved arrangement of doors therefore will not interfere with or impede the passing of individuals in front of the compartment.

Another object or feature of this invention is to provide a structure having doors which, when closed, will completely enclose the front opening of the structure, and which, when open, will in effect result in separate partitions to thereby divide the whole structure into one having a number of open faced compartments corresponding to the number of doors employed. Thus, each particular compartment may be assigned to an individual or group of individuals so as to provide for an orderly and well organized system for controlling the property of the individuals, thereby reducing loss due to theft or misplacement of property. Furthermore, with the doors stationed in their opened position to form separate com-

partments, individuals in one compartment will not have free access to an adjoining compartment without entering from the front of that latter compartment.

Another object of this invention is to provide improved supporting means for the doors that will permit of adjustment of the doors bodily or angularly in any direction or plane, or adjustment relative to one another. This is an important improvement in a structure wherein the doors are required to be actuated simultaneously and controlled by a master door, because, where doors are supported and operated in a structure or building wherein the floors or compartment framework may settle or otherwise be moved out of position, some compensating means must be present to adjust the doors to bring them to their proper position, otherwise the doors may bind in their movements or fail to register properly when closed.

A further object of this invention is to provide improved means for preventing damage to the door supporting structure by sudden thrusts inwardly on any door, such as, for example, those due to a person accidentally falling against the same, wherein the strain would be transmitted directly against the supporting or door holding mechanism.

Other objects and advantages will hereinafter appear to those skilled in the art when considered in connection with the accompanying drawings, in which:

Figure 1 is a fragmentary top plan view of a preferred form of my invention;

Figure 2 is a fragmentary front elevational view of the compartment showing the doors or closures in their open position;

Figure 3 is a transverse sectional view taken on the line 3—3 of Figure 1, showing the end compartment substantially enlarged with the door in closed position;

Figure 4 is an enlarged fragmentary top plan view of the upper controlling and supporting assembly;

Figure 5 is an enlarged view of the lower supporting assembly on one of the doors looking upwardly from the floor and corresponding to a view taken substantially along the line 5—5 of Figure 9;

Figures 6 and 7 are enlarged fragmentary sectional views taken through the centers of the upper and lower door supporting and pivoting means, respectively;

Figures 8 and 9 are enlarged vertical views

corresponding to the position of the door as shown in Figure 3 and showing the door supporting and pivoting means in greater detail;

Figure 10 is a fragmentary elevational view of the safety guide mounted in the compartment;

Figure 11 is a plan view of the safety guide adjacent the top of the door; and

Figure 12 is a detail view in perspective of the upper supporting and actuating link or arm.

For the purpose of illustrating my invention I have chosen one specific embodiment which is adapted to be incorporated in a school building wherein the compartment takes the form of a wardrobe or closet adapted to receive wearing apparel, books, etc., and is to be closed by a series of connected doors such as may have blackboards mounted on the outer sides thereof, particularly when the compartment is in a classroom.

The compartment, indicated generally at 11, has a back wall 12 and end walls 13 which may be a permanent built-in part of the building structure. The walls may be conventionally reinforced by a wooden framework or grounds upon which shelves, individual lockers, clothes racks, hooks, etc. can be secured. A ceiling 14 is provided with a screen or ventilating opening 15 for passage of air. The floor may be part of the room floor or may be a separate floor for the compartment. It is obvious that, where the situation demands, such a compartment may be installed independently in the room and comprise a structure having its own separate walls, ceiling, and floor, as, for example, a complete wardrobe cabinet of wood or metal.

As shown in Figure 1, the front opening is enclosed by a series of doors 17, 18, 19 and 20, which may be of any number and which lie in an end-to-end relationship when closed; with their edges 22 contacting with one another. The outer edge of the extreme right hand door 20, as shown in this figure, abuts against the inside of the casting 23 when the door is closed. The door 17 is designated the master door, hereinafter to be described, and this door abuts against a supplementary jamb structure 29 when closed. A lock 24 on the door 17 engages a locking plate on the supplementary jamb structure 29 and this lock also has a rod 30 extending vertically upward and which engages a keeper (not shown) at the top of the door. The rod 30 as shown in Figure 1 is encased within a hollow moulding 31, which moulding protects the rod 30 and also adds to the appearance of the structure. This lock is of well-known type and need not be further described here. The intermediate doors 18-19 are substantial duplicates, and while I have indicated only two doors in Figure 1 it is obvious that I may use any number of doors similar to the doors 18 and 19.

In the construction which I have disclosed (Figure 3), the outer surfaces of each of the doors have black boards 16 with chalk trays 21 positioned below the black boards. Panel doors 23 may be substituted for the black board structure where it is deemed preferable. Racks or shelves 25 are shown mounted on the back wall 12, and these shelves have clothes hangers or hooks 26 secured thereto.

From Figures 2 and 3, it will be seen that the doors are shorter than the vertical opening of the front of the compartment, thus leaving a bottom opening extending the entire width of the front opening of the compartment. Air may then circulate through the compartment by entering un-

der the doors and passing out through the ventilating opening 15 in the ceiling. However, I may provide a door which entirely extends the vertical height of the front opening of the compartment and then incorporate an opening in each of the doors to provide for ventilation of the structure; in the latter case, the openings would be protected by bars or a shutter arrangement to prevent an unauthorized entry into the compartment. An exhaust fan or the like can be conveniently connected to the opening 15 to provide for better ventilation of the compartment if desired.

Each of the doors is supported by link pivoting mechanisms 27-28, which mechanisms are secured to the top and bottom of the doors and to the ceiling and floor, respectively, as best shown in Figure 3. The doors are supported and adapted to pivot upon these mechanisms 27-28 from closed to open position, and as shown in Figure 1, the solid lines indicate the closed position of the doors and the dotted lines which run transversely within the compartment indicate the open position of the doors.

I will now describe in detail the link pivoting mechanism 28 which is disposed at the bottoms of the doors, the details of which are best seen in Figures 5, 7 and 9. This mechanism comprises a base or attaching member in the form of a sleeve 32 having the bottom flared outwardly at right angles from the side wall of the sleeve to form a flange plate 33. Screws 34 or the like pass through openings in the flange plate 33 to fasten the sleeve 32 to the floor 35. A pair of flange rings 36 and 37 projecting inwardly from the side wall 100 of the sleeve 32 and are preferably formed integral with said side wall as shown in Figure 7. A central opening is formed in each one of these flange rings 36-37 for the reception of a cylindrical sleeve bushing 38. The bushing 38 is forced 115 into these central openings in the flange rings 36-37, and the opposite ends of the bushing terminate flush with the opposite outer surfaces of the flanged rings.

A ball bearing race structure 39 is adapted to 120 be received on the upper surface of the flange ring 36, the ring acting as a shelf for the support of the bearing structure. The bearing structure consists of a cup 40 in which a ball bearing race 41 is adapted to turn, the cup 40 thus providing a bearing surface in which the ball bearings rotate. The bearing structure 39 has a central opening of the same diameter as the opening which passes through the cylindrical bushing 38. The structure 39 is of conventional type and need 130 not be further described here.

A triangular link or arm 42 is pivotally supported on this base mounting and one end 48 thereof covers the top opening of the sleeve 32. This triangular link member preferably has two 135 of its sides formed of U-shaped or channel cross-section and the other side is preferably flanged to be of angle cross section. A stem 43 projects at right angles from the end 48 of said triangular link member, and this stem 43 is received within 140 the sleeve 32. The stem, therefore, passes through the center of the bearing structure 39 and is rotatably received within the bushing sleeve 38. Both the stem and bushing terminate flush with the lower surface of the inwardly projecting 145 flange ring 37. The stem 43, in turn, has a cylindrical opening 44 passing longitudinally therethrough. A rivet 45 is received in this central opening 44 with its head resting on the triangular link 42 and its opposite end peened or swaged; 150

as at 46, upon the plate or washer 47, to hold the stem 43 of the triangular bracket member 42 in the mounting base. The plate or washer 47 is of greater diameter than the end of the stem 43 or 5 the sleeve bushing 38, and it engages the under side of the inwardly projecting flange ring 37. It will be seen that the sleeved bushing 38 and ball bearing structure 39 facilitate free pivoting of the stem 43 therein and the ball bearing also carries 10 any end thrust from the weight of the door.

The link or arm member 42 has a pair of upwardly extending ears 51 which are formed integral therewith. These ears 51 have central openings for the reception of elbow connections or angle bolts 52, the ends 56 of which pass through the central openings of the ears 51 and are rigidly secured therein. A pair of jamb nuts 54 are threaded on the ends 56 of the elbow bolts and are positioned against one side of the ears 51, acorn nuts 55 are then screwed on the extreme ends 56 of the elbow bolts and against the opposite sides of the ears 51. The nuts 54 and 55 are drawn together tightly against the ears to rigidly hold the elbow bolts on the triangular links.

25 Each of the doors carries a pair of flanged lugs 61 which are secured near the base of the door, as by screws or the like. The lugs 61 have flanged toes 62 extending at right angles therefrom. These toes 62 have apertures for the reception of the opposite ends 57 of the elbow bolts 52. Jamb nuts 64 are threaded on the ends 57 of the elbow bolts and abut against the undersides of the toes 62. Acorn nuts 65 are then threaded on the extreme ends 57 of the elbow bolts, and are drawn 30 tightly against the upper surface of the toes 62. It is to be seen that this method of securing the triangular links 42 to each of the doors provides a two point connection to the door, with the other point of the triangular link secured to the sleeve 32; however, it is to be noted here that a single 35 link structure could also be employed with only a one point connection to the door, and still be within the spirit of my invention.

The link pivoting mechanism 27 secured at the 40 top of each of the doors and to the ceiling is similar in its principal aspects to the link pivoting mechanism which I have just described above but differs therefrom slightly as will hereinafter appear. Now referring more particularly to Figures 4, 6 and 8, this top pivoting link mechanism 27 comprises a flanged sleeve 72 which is substantially the same as the sleeve 32, differing therefrom in that the bearing recess 84 is near the flanged peripheral portion 74 rather than 45 the opposite open end of the sleeve as is the case with the sleeve 32. The flanged portion 74 is secured to a cross member 75 (Fig. 3) by means of bolts or the like, passing through the apertures 76 in the flanged portion. The cross member 75 50 preferably consists of a wooden beam which is anchored to the back wall 12, as at 70, and to the lintel 71 above the doors.

The sleeve 72, as best shown in Figure 6, has a 55 pair of inwardly flanged rings 77-78 cast integral therewith and the rings 77-78 have central apertures formed therein. A cylindrical hollow bushing 82 is fixed in the sleeve 72 with its opposite ends tightly secured in the flanged inner rings 77-78. The extreme ends of the bushing 82 are 60 flush with the outer surfaces of the flanged inner rings. A bearing structure 83 is seated in the recess 84 of the sleeve 72. This bearing structure 83 is identical with the bearing structure 39 of the sleeve 32. The bearing structure 83 comprises a cup 80 having a ball bearing race 81 dis-

posed therein, the inner surface of the cup therefore provides bearing surface for the rotation of the bearing race.

The triangular link member or arm 85 is secured in the sleeve 72, as shown in Figure 6, by means of a stem 86 extending at right angles therefrom which passes through the center of the bushing 82 and the bearing structure 83, and is secured therein by means of a rivet 91. The rivet 91 passes through the cylindrical opening 92 extending longitudinally of the stem 86. The head of the rivet 91 abuts the under surface of the triangular link 85 and the opposite end of the rivet 91 is peened or swaged over, as at 93, upon a bearing plate or washer 94. The bearing plate or washer 94 thus rests directly upon the bearing structure 83 and turns with the bearing race when the link 85 is pivoted in the sleeve 72. The weight of each of the doors 17 to 20, inclusive, is thus distributed upon the bearing structures 39 and 83 in the sleeves 32 and 72, respectively.

The triangular link member 85 has oppositely extending ears 101 which have apertures for the reception of elbow connections or angle bolts 103. The angle bolts 103 each have a pair of threaded ends 104 and 105. Each threaded end 104 passes through one of the apertures in the ears 101 and is held therein by means of a jamb nut 106 and an acorn nut 107. The jamb nuts 106 are first screwed on the ends 104 of the bolts 103 and abut 100 the outer surface of the ears 101, then the acorn nuts 107 are screwed against the opposite sides of the ears 101 on the extreme ends 104 of the elbow bolts. A pair of lugs 111 are secured at the top of the inner surface of each of the doors. 105 These lugs 111 have flanged toes 112 extending at right angles therefrom. The flange toes 112 have central apertures for the reception of the ends 105 of the elbow bolts 103. Jamb nuts 114 are screwed upon the ends 105 and against the 110 upper side of the toes 112. Acorn nuts 115 are then screwed on the extreme ends 105 of the elbow bolts and against the under surface of the toes 112. These nuts 114 and 115 are drawn together on the elbow bolts 103 and against the 115 toes 112 to securely hold the tops of the doors to the triangular links 85. At this state of the 120 description, it is now clear that each of the doors is supported by the pivoted link assembly, and each door is free to pivot into the compartment in 125 a counterclockwise direction, as viewed in Figure 1.

The mechanism for opening all of the doors simultaneously will now be described. As shown in Figures 1, 2 and 4, the doors 17, 18, 19 and 20 130 are interconnected by means of connecting rods 121 secured above the tops of each of these doors and operatively connected to each of the upper pivoting mechanisms 27. For specific details of this door operating mechanism, reference is made 135 to Figures 4 and 8 of the drawings. Adjacent to the right hand ears 101, as shown in Figures 3 and 12, a second ear 122 is formed at right angles to the ears 101, this ear being formed integrally with the triangular link 85 through an L-shaped web 120. This second ear 122 is substantially 140 parallel with the triangular link 85 and contains a vertical opening or aperture for the reception of a pivot stud 124. This pivot stud has a shouldered portion seated on top of the ear and has a threaded lower portion extending down through the ear and receiving a nut 125 which bears against the underside of the ear 122. The stud 124 projects through the ear 122 and extends 145 150

above this ear a sufficient length for a purpose to be described later.

The end doors 17 and 20 have single sleeve connectors 128 pivoted on the studs 124 associated with those doors, while the intermediate doors 18 and 19 have double sleeve connectors 141 (only one intermediate door 19 being shown in Figure 4). These sleeve connectors 128 and 141 have eyes 129 and 142, respectively, into which the extended ends of the studs 124 project. Each of these sleeve connectors 128 and 141 is pivotally secured on a stud 124 by means of a cotter pin 131 passing transversely through the stud, a washer 132 being preferably positioned on the stud and beneath the cotter pin. The extended ends of the studs 124 are of sufficient length so that the sleeve connectors may rise or fall thereon to take an aligned position for holding the connecting rods 121 in a horizontal plane. The difference between the single sleeve connector 128 and the double sleeve connector 141 is that the latter has two internally threaded bores 144 extending oppositely from its eye portion 142, while the single sleeve connector has only one internally threaded bore 143. The connecting rods are screwed a predetermined extent into these bores 143 and 144 by being turned in one direction, as the opposite ends of each of the connecting rods 121 and their corresponding bores are oppositely threaded. The front planes of each of the doors may also be adjusted by turning these connecting rods 121 into or backing them out from the sleeves.

Jamb nuts 133 are drawn up on either ends of the connecting rods against these sleeve connectors to prevent turning of the connecting rods in the sleeves. With the sleeves journaled on the studs 124, opening movement of any one of the doors will be correspondingly transmitted to all of the doors.

The extreme left hand door 17 (Figure 1) is preferably the master door, that is, this door is provided with the locking mechanism 24, as described above, and has the usual door knobs or handles 140 on either side of the door for opening it. The door 17 thus is designated as the master or controlling door, but it is obvious that the extreme right hand door 20, or any one of the intermediate doors might be employed as the master door and still be within the spirit of my invention. Another arrangement is that the doors may turn to the left in opening, or opposite to that shown in Figures 1 and 2. This results by simply reversing the parts and can be easily accomplished within the teachings of my invention. When the master door is locked in its closed position, the remaining doors will also be locked closed due to the connected relation of the doors through the connecting rods 121.

It will now be seen that I have provided a novel door supporting and actuating mechanism, and one that will hold the doors rigid and in substantial alignment at all times. If the doors should necessitate realignment over a period of time, due to possible sinking of the floor, or other causes, I provide novel adjusting and compensating mechanism for collecting the doors and bring them to their proper position. Any of the doors may be adjusted forwardly or rearwardly relative to the front opening of the doors by first loosening the jamb nuts 54 on the lower link assembly, and/or the jamb nuts 106 on the upper link assembly. The whole door may then be moved bodily forwardly or rearwardly by adjusting both the opposite nuts 55 and 107 on the

respective elbow connections 52 and 103. The doors may also be moved bodily up or down in a vertical plane if the nuts 64 and 114 be adjusted. By adjusting both sets of nuts, the doors may be moved angularly vertically or horizontally relative to the front opening of the compartment. After adjusting any of the jamb nuts the corresponding acorn nuts are tightened to restore the door to a rigid position.

As best seen in Figures 1 and 2, the top and bottom pivoting mechanisms are disposed to one side of the center of each of the compartments when the door is in open position. That is, the flanged sleeves are positioned to one side of the transverse center of the door and the lugs which hold the triangular links to the doors are secured to one side of the central transverse plane of the door. When the doors are opened or closed they move eccentrically or with a translatory swinging motion into and out of the compartment relative to their pivots, each door taking a transverse position in the compartment when opened with the major portion of the door on the inner side of the common plane assumed by the doors when they are in closed position. The doors are thus arranged so that rather than move out into the aisle or space in front of the compartment, they move about their pivots into individual planes practically entirely within the compartment. The inner ends of the doors 17, 18, 19, and 20 then abut against the back wall of the compartment, as clearly shown by the dotted lines in Figure 1. In the latter position, the doors form individual partitions which in effect provide a multiple of smaller compartments within the main compartment. Rubber stops or bumpers 146 are secured to the base board and panel board, near the floor and ceiling, respectively, and these stops 146 limit the inward movement of the doors when opened and protect the back wall of the compartment.

As shown in Figure 2, when the doors are opened the bottom pivoting mechanism 28 is stationed at one side of the entrance of each individual compartment, thus providing a wide entrance to allow free and easy access to all parts of each compartment. Another feature of importance derived from the doors being eccentrically mounted relative to the opening movements is that they turn on a sharper arc due to a shorter radius than would be the case if each of the doors were mounted centrally on the pivoting mechanism. In this way a quicker opening movement is effected. An added feature of the arrangement of the doors being pivoted within the compartment to swing about a point off-set with respect to the plane of the doors, or in other words, with the doors mounted eccentrically on their pivots, is the possible accommodation for wide shelves within the compartment because the doors move to one side upon being opened, as will be clear by referring to Figure 1.

Referring now more particularly to Figures 3, 10, and 11, where I have shown an arrangement for preventing sudden thrusts accidentally or otherwise imposed on the doors from damaging the pivotal supports for the doors, it will be seen that a guide plate or rail 155 is secured to a fixed mounting block 156 as by screws or the like. The inside of the mounting block is preferably flush with the inside of each of the doors and the mounting block is itself a stationary part of the compartment. The guide rail 155 is preferably made of metal and projects or extends into the compartment on an arc curved

- substantially about the pivotal axis of the doors. Each of the doors carries a bracket member or plate 157 near the top thereof, and this bracket member 157 has a flanged extension 158 projecting at right angles therefrom. A roller 159 is rotatably mounted on this flanged extension 158, and contacts with the inner side of the guide rail 155 when in closed position. The roller engages the guide rail to direct the door in its initial opening or final closing movements. If an unusual force or strain is suddenly directed against the front of one of the doors, as by a person falling against the door, a part of the impact will be taken by the guide rail which, by virtue of its curvature, tends to swing the door open and thus relieve the pivotal supports of excess strain. The guide rail and roller also aid in maintaining the doors in alignment when they are closed.
- 20 It is to be understood that this invention is not to be limited to the particular embodiment herein described, and shown by way of example in the drawings, but includes such modifications as fall within the scope of the appended claims.
- 25 What I claim is:
1. In a compartment having a series of connected doors, means in said compartment and spaced rearwardly from the top and bottom of each of said doors for establishing a pivotal axis about which each of the doors may swing, mechanism adapted to pivotally support each of the doors for movement about its axis, said mechanism including a triangular link at the top of the door and having one end mounted on the pivotal axis of the door and connected with the door at a pair of spaced points, a sleeve pivotally carried on one corner of each of said triangular links, and connecting rods adjustably secured in said sleeves for actuating all of said triangular links to simultaneously operate all of the doors, the relative position of the doors being affected by the adjustment of the connecting bars in their corresponding sleeves.
- 45 2. In a compartment having a series of doors, pivots spaced rearwardly from the top and bottom of each of said doors for establishing axes upon which the doors may swing, triangular links mounted on said pivots and each having a two-point connection respectively with the top and bottom of each of said doors, each of said connections comprising a pair of lugs mounted on the inner face of each of said doors and angle bolts having threaded ends received in said lugs and in the triangular links for rigidly supporting said doors on said links, a sleeve pivotally mounted on one corner of each of the triangular links adjacent the tops of the doors, and connecting bars secured in said sleeves for simultaneously actuating all of said doors, said connecting bars
- adapted to be adjusted in said sleeves to change the relative positions of the doors.
3. In combination with a compartment having a plurality of doors operable on the actuation of one of said doors, said doors lying in a common plane when in closed position, each of said doors being operable about fixed pivots stationed out of said common plane, horizontally extending arms supporting said doors on their pivots, and a connecting rod interposed between the planes of said doors and pivots and pivotally mounted upon and carried by said arms, said connecting rod being adapted to move translationally of said compartment responsive to the movement of one of said doors to simultaneously actuate all of said doors.
4. In a structure of the class described, mounting means for a rotatable door, said means comprising a pair of sleeves spaced from the top and bottom of said door and mounted in said structure, an arm journaled in each of said sleeves and secured to said door, a mounting lug on said door adjacent said arm, an L-shaped member having one end adjustably mounted in said lug and the other end adjustably mounted in an aperture in said arm, and means for adjusting the positions of said L-shaped members to vary the angular position of said door.
5. In combination, a compartment having a plurality of doors lying in a common plane when in closed position, bearing means for each of said doors disposed within said compartment and spaced from the plane thereof, means comprising a triangular shaped link pivotally connected with each of said bearing means and having a plurality of arms, means for securing each of said links to one of said doors for supporting the doors for movement about said bearing means, an ear formed on one of the arms of each of said triangularly shaped links, and means pivotally connected with and carried by each of said ears for simultaneously actuating each of said doors for opening and closing the same.
6. In combination, a compartment having a plurality of doors lying in a common plane when in closed position, bearing means for each of said doors disposed within said compartment and spaced from the plane thereof, means comprising a triangular shaped link pivotally connected with said bearing means and having a plurality of arms, means for securing each of said links to one of said doors for supporting the doors for movement about said bearing means, an ear formed on one of the arms of each of said triangularly shaped links, and a plurality of connecting rods carried by and pivotally connected with said ears and adapted upon operation of one of said doors to move translationally to simultaneously open or close each of said doors.

ELLIS J. G. PHILLIPS. 135
